His Attorney.

UNITED STATES PATENT OFFICE.

JESSE J. LINEBAUGH, OF SCHENECTADY, NEW YORK, ASSIGNOR TO GENERAL ELECTRIC COMPANY, A CORPORATION OF NEW YORK.

BARRIER OR ARC-DEFLECTOR FOR DYNAMO-ELECTRIC MACHINES OR THE LIKE.

1,331,936.

Specification of Letters Patent. Patented Feb. 24, 1920.

Application filed March 6, 1918. Serial No. 220,870.

To all whom it may concern:

Be it known that I, JESSE J. LINEBAUGH, a citizen of the United States, residing at Schenectady, in the county of Schenectady, 5 State of New York, have invented certain new and useful Improvements in Barriers or Arc-Deflectors for Dynamo-Electric Machines or the like, of which the following is a specification.

10 My invention relates to barriers or arc deflectors for use on dynamo electric machines or the like provided with commutators and has for its object the prevention of flashovers or arcing between sets of commutator 15 brushes of such machines or between a set of commutator brushes and parts of such machines of opposite polarity or ground, upon the occurrence of heavy overloads or short-circuits.

20 In accordance with my invention, I provide a barrier between adjacent sets of brushes consisting of a cooling device for breaking up and cooling the arc which is produced from the brushes upon the occurrence 25 of a short-circuit or a heavy overload.

The features of novelty which characterize my invention are pointed out with particularity in the claims annexed to and forming a part of this specification. For 30 a better understanding of my invention, reference may be had to the following description taken in connection with the accompanying drawing, in which Figure 1 is a perspective view of a dynamo electric machine provided with my invention; Fig. 2 is a sectional view of the barrier of Fig. 1; Fig. 3 is a plan view of a modified form of my barrier; and Fig. 4 is a sectional view of a further modification.

35 Like numerals of reference are used throughout the several figures of the drawing to designate like parts.

In Fig. 1 of the drawing, there is shown the commutator end of a dynamo electric 40 machine which may be either a direct current motor or generator, or a rotary converter. 1 is the frame of the machine, 2 is the armature provided with a commutator 3 on which sets of brushes 4 bear. The armature and commutator are mounted on a shaft 45

5 which is shown journaled in a bearing 6 and the direction of rotation of the armature is indicated by the arrow. In accordance with my invention I provide a barrier between adjacent sets of brushes 4 comprising 55 a cooling device such as a screen for breaking up and cooling the arc which is produced from the brushes upon the occurrence of a short-circuit or a heavy overload. In the particular embodiment of my invention 60 illustrated, each of these barriers comprises a fine mesh metal screen 7 and a coarse mesh metal screen 8, the coarse mesh metal screen being located in front of the fine mesh metal screen having reference to the direction of rotation of the commutator 3, as clearly seen from Figs. 1 and 2 of the drawing. The wire of the coarse mesh screen 8 should have sufficient thermal capacity to cool the arc 65 down to the point where there is not enough 70 heat left therein to burn either the coarse mesh or the fine mesh screen. The fine mesh screen takes out substantially all the heat that is left in the arc when it reaches this screen and thus puts the arc out. In order 75 to form an arc chute, or in other words, to make the arc flow upwardly from the commutator instead of toward the armature or the bearing 6, I provide members 9, 9'' of 80 insulating material at each end of the commutator, these members extending from a set of brushes to its corresponding barrier. I have shown these members as completely 85 encircling both ends of the commutator and spaced inwardly a slight distance from both 90 ends so that the ends of the bars project beyond these members. I prefer to have these members completely encircle the commutator for mechanical reasons, but find that, so far as they are necessary to form an arc 95 chute, they need only extend from a set of brushes to its corresponding barrier. A convenient way of mounting the metal screens is by providing an insulating member 10 in front of which both the metal screens are 100 located having reference to the direction of rotation of the commutator, and to which the metal screens are clamped by means of bolts engaging members 11. The insulating member 10 extends completely across the

commutator from member 9 to member 9'', and it is supported by these members 9, 9'' by means of brackets 12, 12'. In order to support the metal screens and to prevent their 5 coming into contact with the commutator and thereby short-circuiting it, I provide members 13 of insulating material which may be fastened to the members 9, 9'' and 10. These insulating members 13 are U-shaped and may be provided with grooves 14 in which the screens are mounted.

A barrier constructed as described above will diffuse and cool an arc, which is produced from the brushes upon the occurrence 15 of a short circuit or a heavy overload, and will prevent any burning or damage, which would otherwise be caused to the brush rigging, commutator and other parts of a dynamo electric machine.

20 In the modification shown in Fig. 3, I have mounted the screen differently than that shown in Figs. 1 and 2, and have done away with the insulating member 10. In the construction of this figure, a fine metal screen 7' and a coarse metal screen 8' extends across the commutator between adjacent sets of brushes and are fastened to the insulating members 9' by means of bolts and members 11'. The coarse metal screen 25 in this construction is also located in front of the fine mesh metal screen having reference to the direction of rotation of the commutator, and both these screens are prevented from coming into contact with the 30 commutator by an insulating member 13' which is also supported by the insulating members 9' located at each end of the commutator.

In the modification shown in Fig. 4, the 40 fine mesh screen 7' and the coarse mesh screen 8' are mounted substantially the same way as are the screens in Fig. 3. The end portion of the screens away from the commutator, that is, the portions 7' of the fine mesh screen and the portions 8' of the coarse mesh screen are bent backward with reference to the direction of rotation of the commutator so as to act as a barrier against any portion of the arc from the brushes which 45 would tend to escape over the barrier if these portions of the screens were not interposed into the path of the arc.

I desire it to be understood that my invention is not limited to the particular arrangement shown and described, and I aim in the appended claims to cover all modifications which do not depart from the spirit and scope of my invention.

What I claim as new and desire to secure 60 by Letters Patent of the United States, is:—

1. In combination, a commutator, sets of brushes therefor, and barriers located between adjacent sets of brushes, each of said barriers comprising a fine mesh metal screen 65 and a coarse mesh metal screen.

2. In combination, a commutator, sets of brushes therefor, and barriers located between adjacent sets of brushes, each of said barriers comprising a fine mesh metal screen and a coarse mesh metal screen, said coarse mesh metal screen being located in front of said fine mesh metal screen having reference to the direction of rotation of said commutator. 70

3. In combination, a commutator, sets of 75 brushes therefor, barriers located between adjacent sets of brushes, each of said barriers comprising a metal screen, and members of insulating material located at each end of the commutator, each of said members extending from a set of brushes to its 80 corresponding barrier.

4. In combination, a commutator, sets of brushes therefor, barriers located between adjacent sets of brushes, each of said barriers comprising a fine mesh metal screen, and a coarse mesh metal screen, said coarse mesh metal screen being located in front of said fine mesh metal screen having reference to the direction of rotation of said commutator, 85 and members of insulating material located at each end of the commutator, each of said members extending from a set of brushes to its 90 corresponding barrier.

5. In combination, a commutator, sets of 95 brushes therefor, and barriers located between adjacent sets of brushes, each of said barriers comprising an insulating member and a metal screen supported thereby, said metal screen being located in front of said 100 insulating member having reference to the direction of rotation of said commutator.

6. In combination, a commutator, sets of 105 brushes therefor, barriers located between adjacent sets of brushes, each of said barriers comprising an insulating member and a metal screen supported thereby, said metal screen being located in front of said 110 insulating member having reference to the direction of rotation of said commutator, and members of insulating material located at each end of the commutator, each of said members extending from a set of brushes to its 115 corresponding barrier.

7. In combination, a commutator, sets of 115 brushes therefor, barriers located between adjacent sets of brushes, each of said barriers comprising an insulating member, a fine mesh metal screen and a coarse mesh metal screen, said coarse mesh metal screen 120 being located in front of said fine mesh metal screen and both of said screens being located in front of said insulating member having reference to the direction of rotation of said commutator.

8. In combination, a commutator, sets of 125 brushes therefor, barriers located between adjacent sets of brushes, each of said barriers comprising an insulating member, a fine mesh metal screen and a coarse mesh 130

metal screen, said coarse mesh metal screen being located in front of said fine mesh metal screen and both of said screens being located in front of said insulating member having reference to the direction of rotation of said commutator, and members of insulating material located at each end of the commutator, each of said members extending from a set of brushes to its corresponding barrier.

In witness whereof, I have hereunto set my hand this 4th day of March, 1918.

JESSE J. LINEBAUGH.
